UNITED STATES PATENT OFFICE.

DAVID WESLEY HOWELL, OF SHELLMAN, GEORGIA.

PEANUT-SHELLER.

1,286,007.

Specification of Letters Patent. Patented Nov. 26, 1918.

Application filed February 28, 1918. Serial No. 219,652.

To all whom it may concern:

Be it known that I, DAVID W. HOWELL, citizen of the United States, residing at Shellman, in the county of Randolph and 5 State of Georgia, have invented certain new and useful Improvements in Peanut-Shellers; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

This invention relates to new and useful improvements in peanut shelling machine and consists of a simple and efficient device of this nature having various details of construction, combinations and arrangements 20 of parts which will be hereinafter fully described, shown in the accompanying drawings and then specifically defined in the appended claim.

25 My invention is illustrated in the accompanying drawings which, with the letters of reference marked thereon, form a part of this specification and in which:

Figure 1 is a central vertical sectional 30 view through the machine.

Fig. 2 is a top plan view.

Fig. 3 is a sectional view on line 3—3 of Fig. 1.

Fig. 4 is an enlarged detail sectional view 35 through the cylinder and shelling plates.

Fig. 5 is a detailed plan view of two of the shelling plates and wedges separating the same.

Fig. 6 is an enlarged sectional view 40 through the shelling plates, and illustrating the wedge in elevation, and

Fig. 7 is an enlarged detailed view of one of the adjustable shelling plates.

Reference now being had to the details of 45 the drawings by numerals:

1 designates the frame of the apparatus having a hopper 2 hinged as at 2' to the frame and which hopper has journaled in the walls thereof a shaft 3 to which the cylinder 4 is keyed. Said cylinder has a series of bars 5 mounted upon lugs 5' projecting therefrom and which are adapted to crush the shells of the peanuts as they are fed from the hopper into the casing about the 55 cylinder.

On reference to Figs. 3 and 4 of the draw-

ings, it will be noted that the inner walls of the casing are provided with curved recesses or arcuate grooves 22' and in which recesses the ends of the cross bars 22 are mounted loosely. Each of said bars has a metallic plate 23 secured to its inner edge by screws or otherwise, as shown clearly in Figs. 6 and 7 of the drawings. Said plates which have their faces in planes at angles to each other 65 have interposed between same, adjustable wedges 24 which engage recesses in the edges of plates 23. Rods 28 are fastened one to the plate 23' and another in alinement thereto secured to the adjacent wedge 24, and a 70 coiled spring 27 fits over said bars and bears intermediate said plate 23' and the adjacent wedge 24. Said spring should be of sufficient strength so that its tension will hold by pressure the different plates 22 when 75 wedges are interposed between the same in different adjusted positions.

Intermediate the lower portions of the inclined walls 22' is an exit opening 22^a leading into a passageway 10, which latter leads 80 to the fan chamber 8^x in which the fan 9 is mounted upon a shaft 8. The said passageway also communicates with a passageway 11 which leads to the receptacle 12 into which shells and foreign matter are forced 85 by the draft from the fan. A belt 6 passes over a pulley 7 upon the shaft 8 and also over a pulley 31 upon the shaft 3, affording means for driving the cylinder 4. A belt 25 passes about a pulley 26 upon the shaft 8 90 and also about the cylindrical screen 20. A pulley 3^a is fastened to the end of the shaft 3 and is driven from any suitable source of power not shown.

In the bottom wall of the passageway 10 95 is a trough 13 and 15 designates a rod passing through the walls of said trough and upon which one end of the vibrating hopper 14 is mounted, the outer end being provided with a downwardly and inwardly extending 100 exit pipe 19 leading into one end of the cylindrical screen. A rod 16 is pivotally mounted upon a pin 17 and has pivotal connection through the medium of the pin 16^x with one end of the vibrating hopper, shown 105 clearly in Figs. 1 and 3 of the drawings, and the free end of the rod 16 rests in the circumferentially grooved cam 17', shown clearly in Fig. 2 of the drawings, and serves as a means for imparting a vibratory movement to the hopper 14 when the apparatus is 110 in motion.

In operation, the peanuts to be shelled are placed in the hopper 2 and pushed into the chamber in which the cylinder 4 rotates. The bars coming against the peanuts will crack the shells and the meats will fall through the spaces intermediate the plates 23, the bars carrying the latter being adjustable in order to adapt the machine to shell peanuts of different sizes. As the shells and meats fall upon the inclined walls 22^x they will make exit through the opening 22^a where the blast of air from the fan will cause the shells and any other foreign matter that may be contained therewith to be forced up through the inclined passageway 11 into the receptacle 12. The peanuts falling into the hopper 14 will be deposited through the pipe 19 into the interior of the rotary screen 20, the mesh-work of which will be of sufficient size to permit the seconds and split meats to pass through where they may be caught in a suitable receptacle placed underneath, while the whole meats will pass through and make exit through the end of the cylinder.

By the provision of an apparatus for shelling peanuts made in accordance with

my invention, it will be noted that the parts are made adjustable so as to permit peanuts of different sizes to be shelled, the adjustment being by the position the inclined wedges hold relative to the bars frictionally held thereby causing the plates to be held different distances apart.

What I claim to be new is:

A peanut sheller comprising a casing having walls the inner faces of which are provided with arcuate grooves, a series of bars with the ends mounted in said grooves and recessed plates secured to each bar, wedges movable in said recesses and interposed between the bars and yielding means bearing against the series of bars and plates to hold same in different adjusted positions, a shaft journal in the casing and a cylinder rotating with the shaft and having bars adapted to coöperate with said plates or separating for breaking the shells of peanuts.

In testimony whereof I hereunto affix my signature in presence of two witnesses.

DAVID WESLEY HOWELL.
